UNITED STATES PATENT OFFICE.

LEONARD F. CURRIER, OF SALISBURY, MASSACHUSETTS.

TOP-PROP BLOCK.

SPECIFICATION forming part of Letters Patent No. 230,618, dated August 3, 1880.

Application filed April 9, 1880. (No model.)

To all whom it may concern:

Be it known that I, LEONARD F. CURRIER, of the town of Salisbury, State of Massachusetts, have invented Improvements in Carriage-

5 Top Props, of which the following is a specification.

This invention relates to the coverings of top-props of carriages; and it consists in a sleeve or tube, formed of rubber or other suitable elastic material, with a cylindrical interior or passage of a diameter to receive the wooden body of the block, and with a corresponding exterior outline of cross-section, except that a longitudinal rib is formed thereon, 15 to serve as the cushion or buffer for the top bows when turned down.

Figure 1 is an end elevation of my improved covering. Fig. 2 is a transverse section thereof, shown as mounted upon the interior wooden 20 body or block. Fig. 3 is a longitudinal vertical section taken as on line Y Z, Fig. 2, but also showing the prop in elevation and in place in the block, the seat-rail being shown in transverse section, and the top-joint eye, the inner 25 washer, and cap-nut all in vertical section.

In said drawings, *a* represents my improved covering, and *b* is the longitudinal rib formed thereon. The wooden body is shown at *c*, in which is the axial passage *d*, to receive the 30 prop *e*, which extends from rail *f*. The washer *g*, joint-eye *h*, and cap-nut *i* are only shown to exhibit the relation of the several parts.

The body *c* may be formed of wood, by the well-known rounding-machines, with great fa-

cility and at trifling cost, and the sleeve *a* may 35 be advantageously cemented upon the body, or it can be stretched thereon so as to obviate danger of displacement.

By forming covering *a* with a corresponding cylindrical interior and exterior, with the narrow rib *b* raised upon such exterior, the sleeve 40 may be thin, and consequently of good material, thereby producing a good article at small cost, the raised rib furnishing a sufficient cushion for the bows.

I am aware that rubber coverings for top-prop blocks have been formed with a semi-circular semi-oval exterior outline of cross-section, and with an interior passage or bore of a size to receive a body having a passage to 45 receive the iron prop, such interior body being formed as a segment of a circle, and the passage in such covering corresponding thereto; and I make no claim to a covering so formed. Neither do I claim, broadly, or in the abstract, 50 the rib *b*, as the same is of common use upon top-prop blocks formed entirely of rubber; but

What I do claim as my invention is—

As an improved covering for top-prop blocks, a sleeve of rubber having a circular interior 60 wall or outline of a diameter to receive the body *c*, and with a cylindric exterior, with the arc-like rib *b* projecting therefrom, substantially as specified.

LEONARD F. CURRIER.
